US00D907175S

(12) **United States Design Patent** (10) Patent No.: **US D907,175 S**
Roth (45) Date of Patent: ** Jan. 5, 2021

(54) **DRAIN PAN MOUNTABLE WATER SENSOR**

(71) Applicant: **Roth Technologies LLC**, San Antonio, TX (US)

(72) Inventor: **Ronald B. Roth**, San Antonio, TX (US)

(***) Term: **15 Years**

(21) Appl. No.: **29/686,423**

(22) Filed: **Apr. 4, 2019**

(51) **LOC (13) Cl. 23-01**

(52) **U.S. Cl.**

USPC **D23/208**

(58) **Field of Classification Search**

USPC D23/200, 202, 208, 303; D10/52, 56, D10/101

CPC B01D 5/006; B01D 35/30; C02F 1/002; C02F 1/003; G08B 21/20

(57) **CLAIM**

The ornamental design for a drain pan mountable water sensor, as shown and described.

DESCRIPTION

FIG. 1 is a perspective view of the drain pan mountable water sensor showing my new design;

FIG. 2 is front elevational view thereof;

FIG. 3 is a back elevational view thereof;

FIG. 4 is a left elevational view thereof;

FIG. 5 is a right elevational view thereof;

FIG. 6 is a top elevational view thereof; and,

FIG. 7 is a bottom elevational view thereof.
